CLAIM

The ornamental design for a wrench profile, as shown and described.

DESCRIPTION

FIG. 1 is a perspective view of a wrench profile;
FIG. 2 is a top elevational view thereof;
FIG. 3 is a sectional-cut view taken about line A-A in FIG. 2;
FIG. 4 is a sectional-cut view taken about line B-B in FIG. 2; and,
FIG. 5 is a close up front elevation view thereof.
The broken line showing a wrench body and is included for the purpose of illustrating environmental structure and forms no part of the claimed design.
